UNITED STATES PATENT OFFICE.

JOHN E. LIMEBURNER, OF SWARTHMORE, PENNSYLVANIA.

DESIGN FOR A NOSEPIECE FOR EYEGLASSES.

SPECIFICATION forming part of Design No. 34,816, dated July 23, 1901.

Application filed June 6, 1901. Serial No. 63,478. Term of patent 7 years.

To all whom it may concern:

Be it known that I, JOHN E. LIMEBURNER, a citizen of the United States, residing at Swarthmore, in the county of Delaware, State of Pennsylvania, have invented and produced a new and original Design for a Nosepiece for an Eyeglass, of which the following is a specification, reference being had to the accompanying drawings, forming part thereof.

10 The leading feature of my design for a nosepiece for an eyeglass is a plate having therein a series of openings successively of reduced diameters, said plate having its sides converging from top to bottom and the opening of the widest diameter being at the top of the plate, where the latter is the widest.

15 Figure 1 represents a side elevation of a nosepiece embodying my design. Fig. 2 represents a section thereof on line *x x*.

20 In the drawings, A designates a nosepiece for an eyeglass, the same consisting of the

plate B and arm C on the side thereof. The plate B has its sides converging from top to bottom. In the plate in the direction of the length thereof are openings D, the same being successively of reduced diameters. The opening of the widest diameter is at the top of said plate, where the latter is the widest. The other openings, which are successively reduced in diameter, occupy respective parts 25 of the plate as the widths of the latter decrease in the order of said openings to the narrow bottom of the plate.

Having thus described my invention, what I claim as new, and desire to secure by Letters 30 Patent, is—

The design for a nosepiece for an eyeglass substantially as shown and described.

JOHN E. LIMEBURNER.
